F. H. LANGMUIR

TRUNK

Filed Dec. 19, 1925

FIG. 1.

FIG. 2.

FIG. 3.

WITNESS:

John W. Kitchell.

INVENTOR
Frank H. Langmuir
BY
Bissell and Harding
ATTORNEYS.

UNITED STATES PATENT OFFICE.

FRANK H. LANGMUIR, OF WOODBURY, NEW JERSEY, ASSIGNOR TO BELBER TRUNK & BAG COMPANY, OF PHILADELPHIA, PENNSYLVANIA, A CORPORATION OF PENNSYLVANIA.

TRUNK.

Application filed December 19, 1925. Serial No. 76,377.

The object of my invention is to provide a trunk having edges, corners and reinforcing pieces of peculiar contours and which provide a construction adapted to increase 5 the durability and enhance the appearance of the trunk.

Preferred embodiments of the invention are shown in the accompanying drawings, in which—

10 Fig. 1 is a perspective view of a part of a trunk body.

Fig. 2 is a perspective view of one of the corners of a trunk body embodying my invention.

15 Fig. 3 is a view, similar to Fig. 2, of a modification.

Fig. 4 is a vertical section, on the line 4—4 of Fig. 2, through the top and one side of the trunk body of Fig. 2.

20 Fig. 5 is a similar view, on the line 5—5 of Fig. 2, through the trunk body of Fig. 3.

In Figure 1, I have shown the upper part of a trunk body standing on end, which is the normal position of a wardrobe trunk.

25 For the sake of simplicity I have not shown the body divided into the two compartments of which the trunk is composed, as this would involve the illustration of details unrelated to the present invention.

30 The trunk body of Fig. 2 comprises a top *a* and sides *b* and *c*, and longitudinally extending reinforcing strips *d*. The top *a* overlies the sides, and the side *b* overlaps the side *c*.

35 The top is bevelled along its edges at an angle to its face of about 45 degrees to form the bevel edges *a'*, *a'*. At the corner the adjacent edges are cut away at about equal angles to the bevels *a'*, *a'*, to form a bevel corner *a²* having the form of a trapezoid.

40 The side *b* has an upper lateral edge which extends at right angles to its face and which underlies and abuts against the top. The side *b* is bevelled along its vertical edge at an angle to its face of about 45 degrees to form the bevel edge *b'*. At the corner, the edge is cut away to form a bevel corner *b²*, having the form of a rhombus, that extends parallel to and flush with the face of the 45 bevel corner *a²* of the top *a*.

45 The side *c* has an upper lateral edge which extends at right angles to its face and which underlies and abuts against the top, and a vertical edge which extends at right angles

to its face and abuts against the side *b*. At 55 the corner, the edge is cut away to form a bevel corner *c²*, having the form of a triangle, that extends parallel to and flush with the faces *a²* and *b²*, forming with them a hexagonally shaped bevel corner *a², b², c²*. 60

Extending adjacent each edge of each of the members *a*, *b* and *c*, and on the outside thereof, is a reinforcing strip *d*. The outer edge of each strip is bevelled to form a face *d'* parallel and flush with the adjacent bevel edge *a'* or *b'*; thereby forming a bevel edge *y*, as shown in Fig. 1. Each strip *d* diminishes in thickness from its outer edge forward its inner edge, thereby providing a face sloping rearward toward the face of 70 the member *a*, *b* or *c* to which it is applied.

At each corner the strips are cut away to form triangular shaped bevelled faces extending parallel to and flush with the face of the hexagonal shaped bevelled corner formed by cutting away the edges of the top and sides. These triangular bevelled faces, together with said hexagonal bevelled face, form a triangular shaped bevel corner *x*. When the described elements are assembled, the trunk presents the appearance shown in Fig. 1. Metal corner pieces are usually applied to the trunk, but these corner pieces are not shown, as they would conceal the structure that it is desired to illustrate.

The construction shown in Figs. 3 and 5 is the same as that shown in Figs. 2 and 4 except that the top *e* extends within the sides *f* and *g*. In such a construction it is 90 desirable to form two of the bevelled faces *f', f'*, on the side *f* and the third bevelled face *g'* on the side *g*.

Having now fully described my invention, what I claim and desire to protect by Letters 95 Patent is:

1. A trunk body provided with bevelled edges and provided also with bevelled corners each of whose faces extends in a plane oblique to all the faces of the three adjacent trunk walls and all the faces of the three adjacent bevelled edges, and reinforcing strips secured to the outside of the walls and adjacent to and along opposite sides of said bevelled edges and bevelled to form faces in 100 substantially the same planes as the faces of said bevelled edges.

2. A trunk body provided with bevelled

edges and provided also with bevelled corners each of whose faces extends in a plane oblique to all the faces of the three adjacent trunk walls and all the faces of the 5 three adjacent bevelled edges, and reinforcing strips secured to the outside of the walls and adjacent to and along opposite sides of said bevelled edges and bevelled to form faces in substantially the same planes as the 10 faces of said bevelled edges and corners.

3. A trunk body comprising walls forming sides and top, one of three adjacent walls overlapping the edges of other two walls, and one of the last named two walls overlapping 15 the edge of the other, the edges of the overlapping wall and the corner of the wall being bevelled, and strips secured to the outside of the walls and adjacent to and along opposite sides of said bevelled edges and 20 bevelled to form faces in substantially the same planes as the faces of said bevelled edges and corner.

4. A trunk body provided with bevelled edges, and reinforcing strips secured to the 25 outside of the trunk walls and adjacent to and along opposite sides of said bevelled edges, said strips being bevelled along their outer edges to form faces in substantially the same planes as the faces of said bevel-

led edges, said strips diminishing in thickness from their outer edges toward their inner edges.

5. A trunk body comprising walls forming sides and top, one of three adjacent walls overlapping the edges of the other two 35 walls, and one of the last named two walls overlapping the edge of the other, the edges of the first wall being bevelled and the edge of the second wall adjacent the edge of the 40 third wall being bevelled, the edges of the three walls being shaped at said corner to provide a bevelled corner whose face extends in a plane oblique to the faces of the three adjacent walls and the faces of the three adjacent bevelled edges, and reinforcing strips 45 secured to the outside of the walls and adjacent to and along opposite sides of said bevelled edges and bevelled to form faces in substantially the same planes as the faces of said bevelled edges, said strips diminishing in thickness from their outer edges toward their inner edges.

In testimony of which invention, I have hereunto set my hand, at Philadelphia, Pennsylvania, on this 14th day of December, 1925.

FRANK H. LANGMUIR.
